JAR CAP TIGHTENER

Eugene O. French, Norway, Maine

Application September 9, 1931. Serial No. 561,949

1 Claim. (Cl. 215—92)

This invention relates to means for fastening the covers on fruit jars of all kinds that are used for packing or storing fruit, preserves, meats, vegetables and the like and the object of the 5 invention is to provide a fastening device which while being simple in construction is efficient in operation.

With this object in view the structure consists of a cover cast in a usual manner except that 10 at the center of the outer surface thereof there are provided two semi-circular ridges which are concentrically arranged upon the cover and about each other at their ends. The upper edges of the ridges are inclined and each inclined edge is 15 provided with three notches. One notch is located at the lower end of the ridge, a notch is located midway between the ends of the ridge and a notch is located at the upper end of the ridge. A bail is pivotally mounted upon the body 20 of the jar in a usual manner and its intermediate portion may be engaged in the said notches so that when the handle of the bail is swung the cover is drawn down in close contact with the mouth of the jar or with the packing which is 25 interposed between the mouth of the jar and the edge of the cover. In the event that the cover does not fit properly upon the jar when the bail is in one set of notches the cover may be turned so that the bail may be brought into another set 30 of notches and may be drawn down as hereinbefore indicated to effectually close the mouth of the jar and retain the contents thereof in air tight condition.

In the accompanying drawing:—

35 Figure 1 is a side elevational view showing the cover applied to the mouth of a jar.

Figure 2 is a similar view taken at a right angle to the view shown in Figure 1.

Figure 3 is a transverse sectional view of the 40 same.

Figure 4 is a top plan view of the cover.

Figure 5 is a detailed side elevational view of the intermediate portion of the cover.

Figure 6 is a diagrammatic view showing the 45 relation of the notches and the inclined edges of the ridges.

As illustrated in the accompanying drawing the jar 1 is of conventional pattern. A handle 2 is pivotally mounted at the sides of the neck 50 of the jar and a bail 3 of wire rod is pivotally connected with the intermediate portion of the handle. A cover 4 is adapted to close the mouth

of the jar 1. Said cover is of circular form and is cast in a single body. The cover 4 is dome shaped and provided around its center with two upstanding circular flanges 5. Said flanges are concentrically arranged upon the cover and joined with each other at their ends. Each flange 5 is provided with an inclined upper edge 6 and each edge is provided with one lower notch 7, an intermediate notch 8 and an upper notch 9. Said notches are located at equal distances apart 65 along the inclined edges 6 of the flanges. The notches 7 of the two flanges are diametrically opposite each other and at the same level. The notches 8 are diametrically opposite each other and at the same level along the inclined edges of 70 the flanges and the notches 9 are similarly located with relation to each other.

When tightening the cover 4 upon the mouth of the jar the intermediate portion of the bail 3 is seated in one of the sets of notches of the 75 flanges 5. The handle 2 is then swung down whereby the bail 3 is moved in a downward direction and the cover 4 is drawn toward the mouth of the jar. Should the cover fail to seat tightly upon the mouth of the jar the handle 2 80 is swung in an upward direction whereby the bail 3 is lifted out of said notches and then the cover 4 may be turned so that another set of the notches may be brought under the intermediate portion of the bail. After this adjustment has 85 been made the bail and handle may be moved in a downward direction as hereinbefore explained and the cover is drawn to seating position upon the mouth of the jar. This manipulation may be repeated until such time as the cover effectually 90 seals the mouth of the jar.

Having described the invention what is claimed is:

A jar cover and fastener of which the former comprises a convex lid having an annular up- 95 standing flange positioned on the top face thereof and concentric therewith, said flange having its upper edge inclined upwardly in opposite directions from diametrically opposite points with notches formed at the peaks of the inclinations 100 and at intermediate points thereon, the fastener comprising a bail having means for moving the same toward and away from the lid and swingable laterally from a position over the lid, the bail being selectively seatable in any pair of 105 notches in said flange.

EUGENE O. FRENCH.
